UNITED STATES PATENT OFFICE.

CLAUS J. WERNER CLASEN, OF DAVENPORT, IOWA, ASSIGNOR TO THE BETTENDORF COMPANY, OF BETTENDORF, IOWA, A CORPORATION OF IOWA.

RAILWAY-CAR CONSTRUCTION.

1,178,491.

Specification of Letters Patent. Patented Apr. 11, 1916.

Application filed February 18, 1914. Serial No. 819,481.

To all whom it may concern:

Be it known that I, CLAUS J. WERNER CLASEN, a citizen of the United States of America, and resident of Davenport, Scott county, Iowa, have invented a certain new and useful Improvement in Railway-Car Construction, of which the following is a specification.

My invention relates to railway-cars and has particular reference to the frame-work and metal sheeting forming the superstructure of an all steel box car, and is directed more particularly to the method of securing the sheets, forming the sides of the car superstructure, to the framing members, whereby a flexibility is effected, at the connection of the sheet to the framing members, to a degree that will prevent the development of buckling strains in the side sheets due to the deflection of the car sides under heavy load and thus make possible the successful use of unusually light or thin sheets in the make up of the envelop or superstructure of the car.

25 In a car in which the superstructure framing, consisting of vertical posts and diagonal braces connected at their lower ends with the side sills of the underframe and at their upper ends to the top side-plate, together with the side sheets, form deep girders supported at the body bolster, they can be and are utilized as the principal load carrying members. When a load is imposed upon a girder of this character and which is supported in this manner, there is naturally a downward deflection, and if the side sheets do not have sufficient inherent stiffness and rigidity by being made of sufficiently thick plates, this deflection will tend to distort the sheets from their original rectangular form to that of a parallelogram or trapezoid and thereby cause them to wrinkle or buckle. In the interest of low cost of production and the avoidance of "dead weight" (the constant transportation of which is one of the greatest items of non-productive expense incident to practical railroading) sheets of sufficient strength and thickness to withstand these buckling strains cannot be employed. My invention is therefore directed to providing means whereby the development of these buckling strains is prevented, thus making possible the use of sheets of unusually light gage.

55 It also consists in providing a frame-

work of a section, and securing the side sheets to same in a manner that the weakening effects of perforating the frame work with the necessary rivet holes is reduced to the minimum. I accomplish this in the manner illustrated in the accompanying drawing in which—

Figure I is a side elevation of a box car showing my improved frame-work with the side sheets attached thereto. Fig. II is a somewhat exaggerated view of the joint or connection between the marginal flanges of two sheets, viewing same from the interior of the car. Fig. III is an enlarged sectional view of this joint at the upper end of Fig. II and Fig. IV is a similar view of the lower end of Fig. II.

Similar reference numerals represent similar parts throughout the several views.

As the underframe of the car forms no part of my present invention, further reference thereto is deemed unnecessary other than to say it is to be equipped with the usual side sill to which my improved car side is to be attached. This is equally true of the roof, as my car side is designed to be used in connection with roofs generally used.

The vertical posts 1 and the diagonal braces 2 are preferably made of Z bars which may be described as a bar having oppositely extending flanges connected by a web plate. To these posts are attached the rectangular shaped side sheets 3. In the drawings the car side consists of eight sections of side sheets, arranged in panels the size of which is determined by the spacing of the vertical Z bar posts. Each sheet has its vertical edges flanged outwardly and is secured to the posts by riveting these flanges to the web of the Z bar posts near the neutral axis thereof. By perforating the web of the Z bars with rivet holes near its neutral axis, practically the entire strength of the original bar is preserved.

It will be noted by reference to Figs. III and IV that in placing the sheets in position the flanges of adjacent sheets are brought in direct contact with each other and both positioned on the same side of the Z bar web to which they are riveted. The rivets are placed nearer the outside edge of the flanges, forming an absolutely tight joint at these edges. The distance from the center of the rivet in the flange to the body of the sheet can be greater than the dis-

tance from the center of the rivet to the free edge of flange. This length of flange from the rivet to the body of the sheet can be such as to permit of a slight separation 5 of the flanges when the entire side structure is subjected to deflection through heavy load, allowing the seam to gap as at 4 at the inside and still maintain a weathertight seal at the outside. Thus it is that a degree 10 of flexibility is effected at the joint between the sheets and the posts that prevents the accumulation of distorting or buckling strains. As seen in Fig. II with the car side slightly deflected under load, the seam 15 would be closed at the upper end of the sheet and gapped or opened at the bottom to an extent as determined by the amount of deflection of the girder formed by the car side. Thus it is that through this flexible joint 20 the use of excessively heavy and stiff sheets, capable of themselves resisting these buckling strains, is avoided and the use of unusually light sheets is made possible. This method of securing the flanges of the sheets 25 to the web of the posts greatly facilitates the construction of the car as the entire rivet is exterior of the car where it is more readily riveted and by much simpler appliances than if the rivet passed through the 30 side of the car by riveting the sheet to the flange of the Z bar post.

What I claim as new is:

1. In a railway box car, the combination 35 of the car sides including a plurality of vertically disposed posts of Z bar section, metallic sheets having their vertical edges flanged, said flanges being connected to the web of said vertical posts at or about the neutral axis thereof,
2. In a railway box car, the combination 40 of the car sides including a plurality of parallel vertically disposed posts, having op-

positely extending flanges and a connecting web, metallic sheets having their vertical edges flanged connecting said posts at their webs, the flanges of adjacent sheets abutting each other and positioned on the same side of the post web to which they are connected.

3. In a railway box car, the combination 50 of a steel frame-work for the superstructure thereof, including vertically disposed posts having oppositely extending flanges and a connecting web and abutting flanged sheets, expansively connecting the webs of 55 said vertical posts.

4. In a car side formed of rectangular metallic plates having their vertical edges flanged, vertical posts having oppositely extending flanges and a connecting web, said 60 flanged sheets arranged to abut one another and secured to the web of said posts in a manner to produce a plain unobstructed surface to said car side.

5. In a car side, the combination of vertical posts and diagonal braces of Z section, rectangular metallic sheets with flanged vertical edges connecting said posts at or about the neutral axis thereof, the flanges of adjacent sheets abutting each other and connected on a vertical line nearer the free edge 70 of said flanges than the body of the sheet whereby that portion of the opposing faces of the flanges between the body of the sheet and the line of connection are capable of receding from and approaching one another when said sheets are under strain.

Signed by me at Davenport, Iowa, this 16th day of February, 1914.

CLAUS J. WERNER CLASEN.
